(57) **CLAIM**

The ornamental design for a toy hand grip for toy top spinner, as shown and described.

DESCRIPTION

FIG. 1 is a front view of the toy hand grip for toy top spinner showing my design;

FIG. 2 is a rear view thereof;

FIG. 3 is left side view thereof;

FIG. 4 is right side view thereof;

FIG. 5 is a top view thereof;

FIG. 6 is a bottom view thereof;

FIG. 7 is a front perspective view thereof;

FIG. 8 is a rear perspective view thereof;

FIG. 9 is a front perspective view showing the design together with broken lines illustrating an associated scoring device and spinner;

FIG. 10 is a rear perspective view of the design and associated structures shown in FIG. 9 together with additional broken lines showing a top and a user's hand; and,

FIG. 11 is a front perspective view.

The broken lines showing the scoring, device and spinner, top and hand are included for the purpose of illustrating environmental structure and manner of use that form no part of the claimed design. The remaining broken lines are included for the purposes of illustrating portions of the toy hand grip that form no part of the claimed design.
